UNITED STATES PATENT OFFICE.

SOLOMON HIMMEL, OF BALTIMORE, MARYLAND.

DISPLAY-RACK.

1,214,461.

Specification of Letters Patent. Patented Jan. 30, 1917.

Application filed March 7, 1913. Serial No. 752,675.

To all whom it may concern:

Be it known that I, SOLOMON HIMMEL, a citizen of the United States, residing at the city of Baltimore, State of Maryland, have invented new and useful Improvements in Display-Racks, of which the following is a specification.

This invention relates to an improved display rack of the type employed in clothing stores for the display of garments and the like, although not limited in its application in this particular.

The object of the invention is to provide an improved display rack so constructed that it may be moved back and forth within a suitable inclosing casing, as desired.

A further object is to provide means for normally preventing rotation of the display rack while being moved back and forth in the case.

A further object is to provide means for causing the display rack to automatically assume the proper position for being returned to the rearward position in the case, after the same has been rotated to display the goods supported thereby.

A further object is to provide means for preventing return of the rack to the rear of the case until the rotatable member has been started to the proper position for the return movement.

The invention will be hereinafter fully set forth and particularly pointed out in the claims.

In the accompanying drawings:—Figure 1 is a plan view illustrating my improved display rack. Fig. 2 is a bottom plan view of the supporting carriage. Fig. 3 is a horizontal sectional view taken on a line parallel with the bottom face of the carriage.

Referring to the drawings, 10 designates a case of any suitable or preferred structure, the bottom wall of which is provided with a channel 11. Located on opposite sides of said channel and parallel with the walls thereof are guides 12 provided with suitable grooves to receive anti-friction balls arranged to support a carriage 13, the arrangement being such that said carriage may reciprocate between said guides. Said carriage is provided with a tubular boss 14 which rotatably supports a shaft 15 carrying a cross head 16 which supports the rack member 17.

The structure thus far described is well

known, being illustrated and described in Letters Patent 991,164 to Andrew E. Miller.

Secured to the lower end of the shaft 15 and below the carriage 13 is a disk 18 which is shown as approximately of the shape of a figure 8. That is to say said disk is generally elliptical in plan view having its opposite sides provided with converging recesses 19 formed by the converging curved edges 20. The general formation of this disk is such that it has a minor and a major axis, because of its width being less than its length. The minor axis is normally arranged parallel with the garment supporting bars 17, the major axis being normally parallel with the walls of the channel 11 in the base of the case. Pivottally connected to the carriage 13, at one end, is a lever 21, the free end of which is engaged by a spring 22 also supported by said carriage. Said lever is provided with a roller 23 which is caused to engage the periphery of the disk 18 and to enter the recesses 19 when the latter come opposite said roller.

It will be noted that the recesses 19, of the disk 18, are so positioned with respect to the minor axis of the disk 18, that the engagement of the roller 23, with either of the recesses 19, positions and normally holds the rack bars 17, at right angles to the walls of the channel 11, and parallel with the rear of the case.

Secured to one wall of the channel 11 is an abutment guide member 24, provided with a shoulder 25, the rear end of said abutment guide member being arranged normally parallel with the side wall of the channel 11, and also parallel with the major axis of the disk 18, when the rack bars are positioned parallel with the rear of the case 10. In the construction illustrated in the drawings, the abutment guide member 24 is shown located adjacent to that side of the carriage 13, supporting the lever 21 and the roller 23.

In the construction illustrated in the drawings, the roller 23 coöperating with the periphery of the disk 18, in addition to its function of positioning the rack, also serves, when engaging either end of the disk 18, to increase the effective major axis thereof to such extent that the shoulder 25 of the abutment guide member 24, acts as an abutment, preventing rearward movement of the rack until said rack is rotated sufficiently to cause the major axis of the disk

to assume its normal parallel relation with the said abutment guide member 24, which positioning, as before described, is automatically completed by reason of the tension of 5 the spring 22, exerted on the lever 21, forcing the roller 23 over the cam inclines into one of the recesses 19. The abutment guide member may be constructed with sufficient 10 rigidity to provide a substantially unyielding abutment for the roller 23, to prevent rotation of the rack when the latter is in its rearward position or moving toward or from such position, or it may be made more or less resilient as conditions may require. 15 It will be readily understood that the shoulder 25 is rendered more or less yieldable, depending upon the degree of resilience of the abutment guide member 24. The resilient portion of the abutment guide member 24 also performs an important function, 20 in that it serves to yieldingly resist rotative movement of the rack, when the carriage 13 has been moved inwardly.

Having thus explained the nature of my 25 invention and described an operative manner of constructing and using the same although without attempting to set forth all of the forms in which it may be made, or all of the forms of its use, what I claim is:—

30 1. In a display device, the combination with a case, of a rotatable rack mounted to reciprocate toward and from the back of the case, and means for cushioning contact of the rack with the case, should rearward 35 movement be imparted when the rack has been rotated from a predetermined position.

2. In a display device, the combination with a case, of a rotatable rack mounted to reciprocate toward and from the back of the 40 case, and a buffer having a resilient portion for cushioning contact of the rack with the case, should rearward movement be imparted when the rack has been rotated from a predetermined position.

45 3. In a display device, the combination with a case, of a rotatable rack mounted to reciprocate toward and from the back of the case, and an abutment guide member attached to the case and provided with means 50 for cushioning contact of the rack with the case, should rearward movement be imparted when the rack has been rotated from a predetermined position.

4. An improvement in display racks comprising 55 a reciprocable carriage, a rotatable shaft supported thereby, a display rack supported by said shaft, means co-operating with said shaft for automatically causing said display rack to assume a predetermined position, and means for cushioning contact of the rack with the case, should rearward movement be imparted when said rack has been rotated from its predetermined position.

5. The combination with a case or compartment, of a rotatable rack movable to and

from a position within said case or compartment, an abutment guide member adjacent the path of reciprocation of said rack, a disk attached to and rotatable with the rack in the same plane as said abutment guide, the width 70 of said disk being less than the length thereof, and means interposed between said abutment guide and said disk and co-operating with the edge of said disk to maintain the major axis of said disk normally parallel 75 with the said abutment guide and to increase the effective length of said disk when partially rotated in forward position, said abutment guide member having an abutment positioned to intercept said interposed means 80 when said disk has been rotated in its forward position.

6. The combination with a case or compartment, of a rotatable rack mounted to reciprocate within the case or compartment toward and from the front thereof, an abutment guide member adjacent the path of reciprocation of said rack, a disk attached to and rotatable with said rack, and means co-operating with said abutment guide and said 85 disk and actuated by said disk, to prevent rearward movement of said rack when partially rotated in its forward position.

7. The combination with a case or compartment, of a carriage to reciprocate within 90 the case or compartment toward and from the front thereof, an abutment guide member adjacent the path of reciprocation of said carriage, a rotatable rack mounted on the carriage, a disk attached to and rotatable 100 with said rack, a member pivoted on the carriage and having a portion riding on the periphery of said disk, said disk having means engaging said member for yieldingly holding the rack in certain positions and actuating said member to abut against said abutment guide member upon partial rotation of the rack when moved from front position.

8. The combination with a case or compartment, of a carriage to reciprocate within 110 the case or compartment toward and from the front thereof, an abutment guide member adjacent the path of reciprocation of said carriage, a rotatable rack mounted on the carriage, a disk attached to and rotatable 115 with said rack, a member pivoted on the carriage and having a portion riding on the periphery of said disk, said disk having means engaging said member for yieldingly holding the rack in certain positions and for moving said member to a position to be intercepted by said abutment guide when the rack is partially rotated in front position, to prevent reciprocal movement of said carriage.

9. In a display device, the combination with a case, of a carriage mounted to reciprocate toward and from the back of the case, a rotatable display rack supported thereby, a disk secured to said rack and provided with 120 125 130

notches, a spring lever provided with a positioning member to engage said notches, and an abutment member for said positioning member when the latter is disengaged from 5 said notches and rearward movement imparted to said rack.

10. In a display device, the combination with a case, of a carriage mounted to reciprocate toward and from the back of the case, a rotatable rack supported thereby, a disk secured to the shaft and provided with notches, a spring lever provided with a positioning member to engage said notches, and a member secured to the case and having an 15 offset portion forming an abutment for the positioning member when the rack is rotated from a predetermined position at the front of the case.

11. An improvement in display racks comprising a reciprocable carriage, a rotatable shaft supported thereby, a display rack supported by said shaft, a cam disk carried by said shaft, and means coöperating with said

disk for causing said display rack to assume a predetermined position when rotated to 25 any position other than said predetermined position.

12. An improvement in display racks comprising a reciprocable carriage, a rotatable shaft supported thereby, a display rack supported by said shaft, a cam disk carried by said shaft, and means coöperating with said disk for causing said display rack to assume a predetermined position when rotated to 30 any position other than said predetermined 35 position, said disk and said coöperating means being provided with complementary interengaging portions.

In testimony whereof I have hereunto set my hand in presence of two subscribing witnesses. 40
